PLANT SPRAYER

Albert Czaczkes, alias Chasques, Boulogne-sur-Seine,
France

Application December 26, 1957, Serial No. 49,027

Term of patent 3½ years

(Cl. D62—2)

Fig. 1 is a side elevation of a plant sprayer embodying my new design.

Fig. 2 is a top plan view thereof.

Fig. 3 is an elevational view of the discharge end thereof.

Fig. 4 is an elevational view of the handle end thereof.

The present application is a continuation-in-part of my copending application Serial No. D. 36,506 filed on the 14th day of June, 1955, now abandoned.

I claim:

The ornamental design for a plant sprayer, as shown and described.
